Primary Examiner — Darlington Ly

(57) **CLAIM**

The ornamental design for an electric motor scooter, as shown and described.

DESCRIPTION

1. Electrical motor scooter
1.1 is a left side elevation view of an electric motor scooter embodying our new design;
1.2 is a right side elevation view thereof;
1.3 is a front elevation view thereof;
1.4 is a rear elevation view thereof;
1.5 is a top plan view thereof;
1.6 is a bottom plan view thereof;
1.7 is a top, front, and left side perspective view thereof;
1.8 is a top, front, and right side perspective view thereof;
1.9 is a top, rear, and left side perspective view thereof; and
1.10 is a top, rear, and right side perspective view thereof.

1 Claim, 10 Drawing Sheets
